UNITED STATES PATENT OFFICE

WALTER E. KIRBY, OF BAY VILLAGE, OHIO, ASSIGNOR TO AMERICAN STOVE COMPANY,
OF ST. LOUIS, MISSOURI, A CORPORATION OF NEW JERSEY

DESIGN FOR A RANGE

Application filed January 3, 1930. Serial No. 34,016. Term of patent 14 years.

To all whom it may concern:

Be it known that I, WALTER E. KIRBY, a citizen of the United States, residing at Bay Village, in the county of Cuyahoga and State of Ohio, have invented a new, original, and ornamental Design for Ranges, of which the following is a specification, reference being had therein to the accompanying drawings.

In the accompanying drawings:

Figure 1 is a perspective view of a range showing my new design, the range being shown in open position and the legs fragmentarily.

Figure 2 is a perspective view of a range showing my new design, the range being shown in closed position and the legs shown fragmentarily.

I claim:

The ornamental design for a range, as shown and described.

In testimony whereof, I hereunto affix my signature.

WALTER E. KIRBY.
